CLAIM

The ornamental design for ear gel for an earphone, as shown and described.

DESCRIPTION

FIG. 1 is a front perspective view of the ear gel for an earphone.

FIG. 2 is a back perspective view of the ear gel for an earphone.

FIG. 3 is a front planar view of FIG. 1 thereof.

FIG. 4 is a back planar view of FIG. 1 thereof.

FIG. 5 is a left side planar view of FIG. 1 thereof.

FIG. 6 is a right side planar view of FIG. 1 thereof.

FIG. 7 is a top planar view of FIG. 1 thereof.

FIG. 8 is a bottom planar view of FIG. 1 thereof.

FIG. 9 is a front perspective view of the ear gel for an earphone.

FIG. 10 is a back perspective view of the ear gel for an earphone.

FIG. 11 is a front planar view of FIG. 9 thereof.

FIG. 12 is a back planar view of FIG. 9 thereof.

FIG. 13 is a left side planar view of FIG. 9 thereof.

FIG. 14 is a right side planar view of FIG. 9 thereof.

FIG. 15 is a top planar view of FIG. 9 thereof; and,

FIG. 16 is a bottom planar view of FIG. 9 thereof.

The features shown in broken lines depict environmental subject matter only and form no part of the claimed design.
